UNITED STATES PATENT OFFICE.

JOHN A. DIRIENZO, OF MADISON, WISCONSIN.

INTERNAL-COMBUSTION ENGINE.

Application filed March 25, 1922. Serial No. 546,838.

To all whom it may concern:

Be it known that I, JOHN A. DIRIENZO, a citizen of the United States, residing at Madison, in the county of Dane and State of Wisconsin, have invented certain new and useful Improvements in Internal-Combustion Engines, of which the following is a specification, reference being had to the accompanying drawings.

10 This invention relates to improvements in internal combustion engines, and more particularly to improvements of the valve structure and arrangement thereof.

An important object of the invention is to 15 provide an intake or exhaust valve for a plurality of cylinders comprising a valve body usually formed integrally with the engine and embodying an elongated bore and a pair of expansible cylinders reciprocable 20 within the valve body and having openings alignable with openings formed in the valve body. Heretofore in valves in which reciprocating cylinders have been employed the cylinders have been of rigid construction 25 and have accordingly become warped and worn in use and permit leakage. This is due to the fact that in the construction of these valves the intake and exhaust valves have been combined in a single structure 30 necessitating partition walls upon the inner cylinder which rigidify the same and prevent proper expansion thereof.

An important object of this invention is to provide a valve cylinder for valves of 35 the type set forth which are longitudinally slotted and formed of a suitable resilient material so that they may be expanded against a similar cylinder or against the walls of the valve bore.

40 A still further object of the invention is to provide an operating mechanism for valve structures of this character.

An additional object of the invention is the provision of a valve of this character 45 which will be very simple and inexpensive in construction, easy to adjust and maintain in adjustment, strong and durable in service and a general improvement in the art.

50 These and other objects I attain by the construction and arrangement shown in the accompanying drawings wherein for the purpose of illustration is shown a preferred embodiment of my invention and wherein

like reference characters designate like parts throughout.

In the drawings:

Figure 1 is a longitudinal sectional view taken through an internal combustion engine embodying valve gearing constructed in accordance with my invention;

Figure 2 is a transverse sectional view taken therethrough;

Figure 3 is a fragmentary plan view showing the drive for the sleeve valves;

Figure 4 is a top plan view of the valve member;

Figure 5 is a sectional view showing a different manner of forming the slot;

Figure 6 is a detail longitudinal sectional view showing the manner of attaching the head to the outer cylinders; and

Figure 7 is a transverse sectional view thereof.

Referring now more particularly to the drawings, the numeral 10 designates an engine, 11 the head thereof, 12, 12^a, 12^b and 12^c cylinders and 13, 13^a, 13^b and 13^c the pistons.

The head 11 is provided with longitudinal bores 14 and 15 forming a gas intake chamber and gas exhaust chamber respectively, each of these chambers having an outlet 15^a whereby it may be connected with the carburetor or exhaust pipe as the case may be. The head is provided with openings 16 communicating with each of the cylinders 12, 12^a, 12^b and 12^c and each of these openings has a branch 17 communicating with the chamber 15 or exhaust branch, and a branch 18 communicating with the chamber 14, or inlet branch.

Disposed within each chamber 14 and 15 are outer and inner expansible sleeve members 19 and 20 respectively. The construction and arrangement of the sleeve members in each of the chambers 14 and 15 being similar, the description of one will herein suffice.

The outer sleeve 19 is provided with openings 21 co-acting with the corresponding branch 17 or 18 of the openings 16 communicating with the cylinder, the openings corresponding in number to the number of cylinders of the engine. The inner expansible sleeve or cylinder 20 is provided with openings 22 which are alignable with the

openings 21 of the sleeve 19. By reciprocating these sleeves the openings 22 and 21 of the sleeves 20 and 19 may be aligned with a given cylinder opening 16 to permit the entrance of a fuel charge or the exhaust of burnt gases, as the case may be.

Each of the sleeves 19 and 20 is longitudinally slotted, as indicated at 23. This slot may be either a zigzag slot, such as illustrated in Figure 4, or a slot having lapped edges, such as indicated at 24 in Figure 5. The peculiar construction of the slot is, however, of small moment provided that it permits of circumferential expansion of the sleeve after the manner of a piston ring in a piston so that the walls of the sleeve are in firm engagement with the wall of the chamber or with the inner wall of the associated sleeve, as the case may be. It is here pointed out that by providing separate exhaust and intake valves the sleeves may be formed of suitable material for each of these purposes. For example, the sleeves of the intake chamber may be formed of steel and not being subjected to the intense heat will maintain their temper sufficiently to afford a tight seal. The sleeves of the exhaust chamber, however, should be formed of cast iron or some other material which will retain its resiliency when subjected to a great degree of heat. The outer surface of each of the sleeves 19 and 20 may be provided with grooves 25 affording recesses for the accumulation of oil for lubricating the sleeves at desired points, no particular arrangement of these grooves being specified with the exception that it is necessary that they are not arranged so that they overlap the opening 16 of the cylinder or the openings of the associated sleeve so as to interfere with proper compression or expansion of the gases in the cylinder and that they terminate short of the slot of the sleeve.

The operating ends of the sleeves 19 and 20 project beyond one end of the chambers and are provided with heads 26 and 27 respectively. The heads 26 and 27 are secured to their respective sleeves 19 and 20 in such a manner as to permit expansion of the sleeve. In the present instance the heads are shown as provided with extensions 26^a and 27^a having screw threads 28 coacting with screw threads formed upon the respective sleeve. In the case of the head 27 these screw threads are formed exteriorly for engagement with interior threads formed upon the sleeve 20. In the case of the head 26 these threads are interior, coacting with exterior threads formed upon the sleeve 19. As in each instance the threaded engagement of the heads with the sleeves is necessarily a loose one to permit of expansion, pins 30 are provided for preventing relative rotation of the heads and sleeves. The inner head 27 has an enlarged portion 29 inter-

posed between its extension 27^a and the head 27 proper against which the end of the sleeve 20 abuts, thereby forming a joint preventing the escape of gases longitudinally of the sleeve.

The head 26 is provided with an opening coinciding with an enlarged or recessed portion 23^a of the slot through which a sealing member 23^b may be directed for engagement in the enlarged or recessed portion 23^a, the sealing member being retained in position by means of a screw plug 26^b and a spring 26^c disposed intermediate the screw plug and sealing member. The sealing member or wedge will be made of softer metal than the cylinder or sleeve with which it coacts so that it will wear away sufficiently fast to keep it continually seated in the recess 23^a to seal the joint. The heads 26 and 27 are provided with arms 31 and 32 affording pivots for a purpose presently to appear.

The intake or exhaust end of the outer sleeve 19 operates within an enlarged recess portion 40 of the bore 14 and is provided with a head 41 similar to the head 26, this head having a bore 42 slightly larger than the end of the sleeve 19. A plug or wedge 43 engages in the slot of the sleeve and is held in such position by means of a screw plug 44 and spring 45. The head is secured in position by means of a securing element 46. Attention is directed to the fact that the engagement of the plugs 23^b and 43 not only tends to seal the ends of the longitudinal slot of the sleeve but likewise maintains this sleeve in expanded position, preventing collapsing or closing of the slot thereof due to the pressure of explosion in any of the cylinders which would tend to decrease the diameter of the outer sleeve and permit escape of the gases of the explosion from one cylinder to another.

The numeral 33 designates a horizontal shaft disposed transversely of the end of the cylinder at which the heads 26 and 27 are disposed and which is supported by suitable brackets 34 secured to the engine. This shaft is driven by a drive member 35 receiving its power from the crank shaft of the engine and embodies cranks 36 and 37 connected with the arms 31 and 32, respectively, by connecting rods 38 and 39 engaged with the cranks and with the pivots carried by the arms. It will be seen that upon rotation of the shaft 33 the sleeves 19 and 20 will be independently reciprocated and because of the peculiar arrangement the openings thereof will have these openings aligned with one another and with the corresponding opening 16 of the cylinder at every second revolution of the crank shaft, the shaft 33 being driven at one-half the speed of the crank shaft. The arrangement of openings shown admits fuel to the cylinders and completely seals each cylinder after the admis-

sion of gas is completed until the charge has been compressed, fired and exhausted. However, the arrangement shown need not be adhered to, any arrangement accomplishing this result being used.

From the foregoing it is believed to be obvious that control valves of the type disclosed herein are particularly well adapted for the use for which they are intended in 10 that they provide against ordinary wear by their expansibility, are light and cheap in construction and may be readily replaced. It will furthermore be obvious that the construction as hereinbefore set forth is capable 15 of some change and modification without materially departing from the spirit of my invention and I accordingly do not limit myself to the specific structure thereof except as hereinafter claimed.

20 I claim:

1. A valve member formed as a tubular body having a slot therein, a head surrounding one end of the body, a securing element carried by the head and engaging the body, 25 and a spring pressed wedge carried by the head and engaging within said slot for effecting sealing thereof.

2. A valve element comprising an elongated tubular body formed with a slot, a ring 30 like head disposed upon one end of the body, a securing member passing through said head and engaging in the body at a point opposite the slot, the opposite point on the head being formed with an opening, a wedge plug engaged within said slot and slideable within 35 said opening, a spring within the opening engaging the plug, and an adjustable abutment for the outer end of the spring.

3. A valve element formed as an elongated 40 tubular body having one end formed with a slot, a ring like head loosely engaged upon said end, a securing member passing through the head and into the body at a point diametrically opposite said slot, the opposite 45 point of the head being formed with an opening, a tapered plug slideable within said opening and engaged within said slot, a spring within the opening engaging the plug, and a screw member threaded into the 50 opening for regulating the tension of the spring.

4. A valve element formed of telescopi- 55 cally engaged tubular sections formed with

slots, a head screwed into the inner section, a head of sleeve like formation surrounding 55 said first named head and having loose threaded engagement exteriorly upon the outer section, the first named head having a portion abutting the end of the inner section for sealing the same, and means on the 60 second named head for sealing the slot in the outer section.

5. A valve element formed as an elongated tubular body having a slot therein, a ring like head having a loose thread connection 65 upon the outside of said body, the loose fitting of the threads permitting expansion of the body, and wedge means carried by the head and fitting within the slot for sealing the same.

6. A valve element comprising a ported cylinder formed of resilient material and slotted from end to end, a head engaging one end of said cylinder, and sealing elements disposed within said slot and maintained in 75 position by said head.

7. In an engine having a bore communicating with its cylinders through ports, a valve mounted within said bore and formed of telescopically engaged sections, the outer 80 section having one end externally threaded and the inner section having the same end internally threaded, a head loosely engaged upon the threaded end of the outer section, and a head having a threaded extension 85 loosely engaged within the threaded end of the inner section, the sections being expansible and the loose fitting of the threads permitting expansion.

8. In an engine having a bore communicating with its cylinders through ports, a valve mounted within said bore and having ports adapted to be brought into registration with the first named ports, said valve being expansible and having one end externally threaded and slotted, a head loosely screwed onto said threaded end, the looseness of the threading permitting expansion of the valve, means for preventing relative 95 rotation of the valve and head, and a spring 100 pressed wedge plug extending into and sealing said slot.

In testimony whereof I hereunto affix my signature.

JOHN A. DIRIENZO.
